(57) **CLAIM**

The ornamental design for a capsule containing washing product as shown and described.

DESCRIPTION

FIG. 1 is a perspective view of our new design for a capsule containing washing product showing our new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a bottom plan view thereof.

The broken contour lines shown in the figures represent the three-dimensional character and contour of the capsule. They are not intended to illustrate material, surface ornamentation, or surface decoration.

The oblique shade lines in the figures show a transparent surface and not surface ornamentation.
